UNITED STATES PATENT OFFICE.

FRED KOLLMANN, OF GREENE, IOWA.

LUBRICATING APPARATUS.

1,278,940.

Specification of Letters Patent. Patented Sept. 17, 1918.

Application filed May 16, 1918. Serial No. 234,887.

To all whom it may concern:

Be it known that I, FRED KOLLMANN, a citizen of the United States, residing at Greene, in the county of Butler and State 5 of Iowa, have invented a new and useful Lubricating Apparatus, of which the following is a specification.

This invention relates to certain improvements in beaters such as used in connection 10 with some types of threshing machines wherein a number of finger carrying shafts are mounted for rotation about individual shafts while rotating collectively about the axis of a main shaft. Where a number of 15 rotating shafts are moved at a high speed about a fixed axis, as in the beaters mentioned, it has been a slow and laborious undertaking to lubricate all of the shafts and has necessitated long delays in the operation 20 of the beaters.

One of the objects of the present invention is to provide simple and efficient means whereby a lubricant can be supplied to the various bearings while the mechanism is in 25 operation.

Another object is to provide lubricating mechanism which can be installed readily in machines of the type described and which are already in use.

With the foregoing and other objects in view which will appear as the description proceeds, the invention consists of certain novel details of construction and combinations of parts which will be hereinafter more 30 fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is an elevation of a thresher beater of the type mentioned and having the present improvements applied thereto, the central portions of the gang of finger shafts being broken away.

Fig. 2 is an enlarged section through one of the heads of the beater, said section being taken on the line 2—2, Fig. 4.

Fig. 3 is a transverse section through a portion of one of the heads, said section being taken on line 3—3, Fig. 6.

Fig. 4 is an end elevation of the beater,

showing the gearing employed for driving the finger shafts of the beater.

Fig. 5 is a section through one of the heads with the cover plate removed, certain 60 parts being broken away.

Fig. 6 is an elevation of the inner side of the cover plate and showing the means employed for conducting a lubricant to the bearings of the gears.

Referring to the figures by characters of reference, 1 designates portions of a thresher structure provided with stationary bearings 2 and 3 in which the main shaft 4 of the beater is mounted for rotation. A gear 5 is 70 coupled to the bearing 2, as shown in Fig. 2, so as to be held against rotation and this gear may be provided with a boss 6 extending into an opening formed in the center of the cover plate 7 of one of the heads of the 75 beater. The heads of the beater, which have been indicated at 8 and 9 are preferably circular and hollow, the chambers therein forming lubricant receptacles having peripheral openings normally closed by screw plugs 10 80 or the like. By removing these plugs the lubricant can be placed in the respective heads.

Each of the heads 8 and 9 has an interior hub 11 which is keyed or otherwise secured 85 to the shaft 4 so that the two heads will rotate together with the shaft.

Journaled in the peripheral portions of the heads 8 and 9 are parallel shafts 12, there being bearings formed in the heads for 90 these shafts, as shown at 13. Leading to each of the said bearings is a feed tube 14, all of the tubes being arranged radially within their heads and having the advancing portions of their inner or free ends 95 beveled as shown at 15. Beater fingers 16 are mounted on the shafts 12 in the usual manner. The shafts 12 are extended through the cover plate 7 of the head 8 and are provided with gears 17. These gears, in turn 100 mesh with intermediate gears 18 which are secured to stud shafts 19 journaled in the cover plate 7. Wings 20 are extended outwardly from the hub 11 in head 8 and are secured to the cover plate at their outer 105 ends by bolts 21 or in any other desired manner. The forward or advancing faces of these wings are grooved as at 22, said grooves leading to the bearings in which the shafts 19 are journaled.

From the foregoing description it will be apparent that when the shaft 4 is rotated,

the heads 8 and 9 and the finger shafts 12 will all be rotated about the axis of said shaft 4 and the gears will cause the shafts 12, at the same time, to rotate about their individual axes. This operation is common to beaters of this type. The advantages in the present structure, however, are that during the above described operation, lubricant contained in the two heads will be gathered up by the advancing beveled ends of the tubes 14 and directed outwardly by centrifugal force to the bearings of the shafts 12. At the same time a portion of the lubricant contained in the head 8 will be directed along the grooves in the wings 20 and supplied to the bearings of the gears 18. Thus the separate lubrication of the individual bearings which has been necessary heretofore is eliminated with the resultant saving of time and labor.

What is claimed is:—

1. A beater for threshing machines including hollow heads constituting lubricant containers, finger shafts journaled in the heads, a central fixed gear adjacent one of the heads, gears on the finger shafts, intermediate gears on one of the heads and mesh-

ing with the fixed gear and the shaft gears, and means within the heads for picking up lubricant during the rotation of the heads 30 and directing it to the bearings of the shafts and gears.

2. A beater for threshing machines including hollow heads constituting lubricant containers, finger shafts journaled in the heads, 35 a stationary gear, gears upon the finger shafts, gears on one of the heads and meshing with the stationary gear and the shaft gears, radial tubes in each of the heads and extending to the bearings of the finger 40 shafts, the inner ends of the tubes being open and having their advancing portions beveled, and wings within one of the heads and having guide grooves within the advancing faces thereof extending to the bearings of 45 the gears on the head.

In testimony that I claim the foregoing as my own, I have hereto affixed my signature in the presence of two witnesses.

FRED KOLLMANN.
